UNITED STATES PATENT OFFICE.

CHRISTIAN WOLD, OF SIOUX CITY, IOWA, ASSIGNOR OF ONE-HALF TO ALEX K. TROUP,
OF WOODBURY, IOWA.

MITER-BOX.

1,033,140.

Specification of Letters Patent.

Patented July 23, 1912.

Application filed January 8, 1912. Serial No. 670,026.

To all whom it may concern:

Be it known that I, CHRISTIAN WOLD, a citizen of the United States, and a resident of Sioux City, in the county of Woodbury 5 and State of Iowa, have invented certain new and useful Improvements in Miter-Boxes, of which the following is a specification.

My invention relates to means for making 10 miter joints and has for its object the construction of a miter box in which joints at any desired angle may be readily and accurately cut.

The invention consists in the construction, 15 arrangement and combination of parts, as will be specifically described and pointed out in the claims.

I have illustrated my invention in the accompanying drawing in which—

20 Figure 1 is a plan view of my invention, and Fig. 2 an inverted plan, one of the end posts being omitted in Fig. 1 and both posts being omitted in Fig. 2. Fig. 3 is a view in front elevation. Fig. 4 is a view in end 25 elevation, both end posts and slide being omitted. Fig. 5 is a detail view of one of the guides or posts with vertical slots or kerfs, showing means for securing it to the bar, a portion of which is shown in cross-section. Fig. 6 is a side view of part of 30 frame showing the square opening for securing the shank of the central guide post. Fig. 7 is an end view of the box opposite from that seen in Fig. 4. Fig. 8 is a detail 35 view of one of the combined feet and corner brackets of the frame.

Referring to the illustration, 1 is the front side of the frame, 2 the rear side and 3, 3 the end pieces secured together at the 40 corners by the brackets 4 secured inside the corners of the frame and formed integrally with the feet 4^a on which the frame rests. The frame is made preferably of metal and is angle-shaped as seen in Fig. 2, a portion 45 of the front side being cut out and disclosing the rear side. The frame is strengthened by the ribs 5 near the center and cross-bars 6 near the ends. A board or plank 7 is secured above the frame by screws 8, 50 forming a platform on which are marked the lines indicating the angles for sawing, as seen in Fig. 1. A bar 9 is hinged to the rear of the side piece 2 by hinges composed of the parts 10 and 11, the former of which 55 is secured to the end of the bar, the latter

to the lower corners of the platform 7, being set into cut-out parts in the corners, and turned up to hinge with the parts 10.

The guide posts 12 with the vertical kerfs are secured to the bar 9 as shown in Fig. 5, 60 the lower end of the posts being smaller and forming a shoulder set into the bar, with nuts 13 on the threaded ends under the bar. The kerfs are narrower at the upper ends to conform somewhat to the shape of a saw 65 and the posts are set at various angles as shown so that the kerfs will all register with a central post on the opposite side of the platform, as presently described. The bar being hinged to the platform permits the 70 box to be folded into smaller space by dropping the guide posts upon the platform as seen in Fig. 7 and indicated in Fig. 4. The side 2 supports a central guide post 14 which is adjustably secured to the head 15 of a 75 rod or shank 16 rotatably secured in the side piece 1 and supported under the platform by braces 17 and 18 secured to the respective side pieces 1 and 2. The free end of the bolt is threaded and bears a nut 19 and between the nut and brace 17 a coil spring 20 encircles the bolt. The nut may be used for adjusting the tension of the spring. Near the head 15 the bolt has a square enlargement 21 adapted to fit a similarly shaped 80 opening in the side piece 1, Fig. 6, the spring forcing the enlargement into the opening where it is held, and supports the guide post 14 in an upright position. The 85 guide post may be laid horizontal with the frame, or nearly so, as indicated in Fig. 1, by pulling the bolt 16 out until the enlargement is free of the side piece. The vertical kerf of the guide 14 may be set to register 90 with any of the guides 12 at any desired angle, as indicated by the lines and figures in Fig. 1, as the post is freely movable in the head and held in place by the shoulder like that seen in Fig. 5, with a nut 22 under the head.

The frame and the guide bar 9 are adapted to be locked together so as to make them rigid by hooks 23 formed on the ends of the bars 6 and the catches 24 pivoted at 25 to the bar. At the ends of the box are retaining posts 26 and 27 movable laterally with reference to the platform and adapted to hold the molding or board at either end in position and also to assist in marking the angles between those shown on the lines. 110

The end posts are made preferably of metal, the upper part being angle-shaped and tapering toward the upper end and the lower part flat. The posts are movably secured 5 by thumb screws 28 and 29 respectively threaded into openings in slides 30 and 31. The slides are right-angled in shape, one part being movable in cut-out parts of the platform 7 above the end pieces, and at the 10 lower corners are the stops 32 and 33 respectively, formed integral with the slides and adapted for rests for the posts and to hold them in upright position. The slides are held against the end pieces by the respective thumb screws 34 and 35 which are inserted through slots 30^a in the slides in threaded openings 36 in the end pieces. The ends of the slides opposite the posts are provided with extra openings 37 at which 15 the posts may be secured if desired, and, by changing the thumb screws securing the slides into the holes in the opposite ends, the slides and posts may be moved the same distance in the opposite direction. When the molding or 20 board to be mitered is placed in the proper position the post 26 or 27 is moved to the opposite side of the guides 12 with the slide and secured by tightening the thumb screws. I have shown the necessary guide posts with 25 vertical kerfs for all usual angles in mitering, but others may be added if desired.

The method of using my invention will be familiar to any mechanic and its practical utility and simplicity, together with the 30 small space into which it may be folded, mark it as an improvement over any similar device now in use.

Having described my invention, what I 35 claim as new and desire to secure by Letters 40 Patent, is,—

1. A miter box consisting of a frame, a bar bearing guide posts hinged to the frame whereby the box may be folded into smaller space when not in use, means for locking the 45 bar to the frame, the guide posts being set in said bar and having vertical kerfs, a

guide post with a vertical kerf rotatably secured to the opposite side of the frame at the middle thereof and adapted to be turned to a position parallel with the base of the 50 frame when not in use, a platform secured to the upper part of the frame and retaining posts slidably secured to each end of the frame.

2. A folding miter box consisting of a 55 frame, a platform secured thereto, a bar bearing guide posts hinged to one side of the frame whereby the posts are folded upon the platform when not in use, means for locking the bar to the frame, the guide posts 60 having vertical kerfs and being secured in said bar, a similar post rotatably secured to the opposite side of the frame and adapted to be turned to a position parallel with the base of the frame when not in use, a slide 65 movably secured to each end of the frame and a post adjustably secured to each of the slides and adapted for securing the material in position when the joints are cut.

3. A miter box consisting of a frame, 70 guide posts with vertical kerfs secured at one side thereof, a platform secured above the frame, a guide post at the opposite side of the frame with a vertical kerf rotatably secured adjustable upon its longitudinal 75 axis to register with the post opposite, a shank to which said post is secured, adjustably secured in a slot in the frame at right angles to the post and having a squared part to fit said slot, a spring for forcing the 80 squared part into the slot whereby the post is held in an upright position, the post being adapted to assume a horizontal position when not in use.

In testimony whereof I have hereunto 85 signed my name in the presence of two subscribing witnesses.

CHRISTIAN WOLD.
